United States Patent Office

Des. 225,590
Patented Dec. 19, 1972

225,590

SUITCASE

Dino Valaguzza, Via Palestro 22,
Milan, Italy

Filed Aug. 14, 1970, Ser. No. 24,492

Claims priority, application Italy Apr. 9, 1970

Term of patent 7 years

Int. Cl. D3—01

U.S. Cl. D87—5

FIG. 1 is a top, front perspective view of a combined coffee maker and warmer showing my new design;

FIG. 2 is a bottom plan view thereof;

FIG. 3 is an elevation view thereof as seen from either end; and

FIG. 4 is an elevation view thereof as seen from either side.

I claim:

The ornamental design for a suitcase, substantially as shown and described.
